COMBINED HIGH CHAIR AND STROLLER

John B. Peterson, Sausalito, Calif.

Application November 14, 1950, Serial No. 12,970

Term of patent 7 years

(Cl. D15—1)

To all whom it may concern:

Be it known that I, John B. Peterson, a citizen of the United States of America, resident of Sausalito, in the county of Marin and State of California, have invented a new, original, and ornamental Design for a Combined High Chair and Stroller, of which the following is a specification, reference being made to the accompanying drawings, forming a part thereof.

Fig. 1 is a side elevation of a combined high chair and stroller, showing my new design;

Fig. 2 is a perspective view on an enlarged scale of the combined high chair and stroller; and

Fig. 3 is a front elevation of the combined high chair and stroller.

I claim:

The ornamental design for a combined high chair and stroller, substantially as shown.

JOHN B. PETERSON.
